UNITED STATES PATENT OFFICE.

WILLIAM WALLACE, OF NEW YORK, N. Y.

DESIGN FOR A CAMPAIGN-BADGE.

SPECIFICATION forming part of Design No. 26,264, dated November 17, 1896.

Application filed September 17, 1896. Serial No. 606,181. Term of patent 3½ years.

To all whom it may concern:

Be it known that I, WILLIAM WALLACE, a citizen of the United States, residing at the city of New York, in the county of New York and State of New York, have produced a new and original Design for Campaign-Badges, of which the following is a specification, reference being had to the accompanying drawings, forming a part thereof.

10 My new and original design is fully disclosed in the following specification, of which the accompanying drawings form a part, in which—

15 Figure 1 is a plan or face view thereof, and Fig. 2 a side view thereof, these two views being deemed necessary to fully illustrate my design.

20 The leading feature of my design consists of the half of a nut-shell, as shown at 5, in which is set a disk 6, in the center of which is a figure 8, which represents one of the candidates of one of the leading parties for the presidency, and the figure 8 is placed within a circle 9, and between the circle 9 and the perimeter of the disk is an annular space 10, 25 the upper left-hand corner of which is provided with a plurality of stars, as shown at 11, which represent the stars of the American flag, and the rest of said space is divided 30 transversely into spaces 12 and 13, which represent the red and white stripes of the flag.

By dividing the nut longitudinally of its

longest axis, and removing the interior thereof, a space or cavity 14 is formed which is substantially round, and the disk or button 6 is secured in this space or cavity in any desired manner, and my invention is not limited to the character of the shell or nut employed, nor to the means for securing the disk or button therein, the leading features of the design being the half of the nut, the interior of which is removed, so as to form the open space or cavity 14, and the disk or button secured therein, so as to practically fill said space or cavity, said disk or button being provided 45 with a circular space, in which is placed a figure representing one of the candidates for the presidency and around which is formed a circular space which is so divided as to represent the American flag.

50 Having fully described my new and original design for campaign-badges, I claim and desire to secure by Letters Patent—

55 The design for a campaign-badge herein shown and described.

In testimony that I claim the foregoing as my invention I have signed my name, in presence of the subscribing witnesses, this 16th day of September, 1896.

WILLIAM WALLACE.
